TEMPERATURE AND PRESSURE RELIEF VALVE.

Application filed April 9, 1927. Serial No. 182,507.

This invention relates to an improved structure for safety valves. Valves of this general type are usually used in hot water heating systems to open the system as a relief 5 against excessive pressure. They are also used in a great number of analogous systems or structure.

According to the present invention, a safety valve is provided, having improved features of construction. One of these features relates to the manner in which the operating parts are related to the valve casing so as to be contained wholly within the casing and yet permit the convenient adjustment 15 of the parts from without the casing. Another feature is in the means for locking the parts in adjusted position. Another feature is in the arrangement for insuring an accurate working of the parts through simple 20 means. Other features of the pressure operated relief means will appear in the detailed description and claims.

In addition to the pressure operated relief means, I have provided a temperature controlled relief means of improved construction. The general improvements in the latter are in the simplicity of its structure and the convenience of renewing the expendable part or fusible plug from without the 30 casing. This temperature controlled relief means has other improved details of construction that will be best understood from the following description and annexed claims.

35 In the accompanying drawings—

Fig. 1 is an exterior view of the valve;

Fig. 2 is a sectional view of the valve with the details of the pressure operable release means arranged to indicate their nature and order of assembly;

Fig. 3 is a sectional view of the valve taken at right angles to Fig. 1 so as to show all the parts, including the temperature controlled relief means in position;

45 Fig. 4 is a detail section on line 4—4 of Fig. 2 with a part of the spring adjusting means shown in position therein; and

Fig. 5 is a side view of one of the cartridges for holding the fusible plug for the temperature controlled release means.

The details of construction and assembly will now be described, referring to the drawings: The valve casing 1 has an enlarged central portion and cylindrical portions for

an inlet port 2, a drain port 3, and an opening at the top in alignment with the inlet port and through which portion 5 the movable parts of the valve may be inserted. The main valve seat 8 is provided at the top of a tubular extension 4 within the enlarged portion of the valve casing. The valve closure 6 is provided with a depending squared guiding member 9, the rounded corners of which contact with the walls of the extension 4 to guide the valve closure 6 in its up and down movements. A rubber or other suitable gasket 7 is provided on the valve closure 6 to make good contact with valve seat 8. The coiled spring 10 rests on top of the valve closure 6 and extends up centrally within the portion 5 of the valve casing. The portion 5 is provided as shown with an exterior thread to receive cap 16. A spring adjusting means is provided for cooperation with the cap 16. It consists in a threaded stem 14, the thread 20 of which is a left handed thread if the thread 19 of the cap 16 is a right handed thread, or vice versa for a purpose to be described.

The stem 14 has fastened at the top, as by an integral member 15, a disc or plate which is provided at its center with a head 18 having a slot therein, in order that the stem 14 may be turned. The cap 16 has a central opening 17 through which the head 18 extends just far enough so as to be conveniently manipulated by a screw driver. Threaded on the stem 14 I provide a disc 12 adapted to bear on the top of the spring 10. This disc 12 is provided with diametrically opposite ears 13 best shown in Fig. 4. These ears 13 are adapted to engage the vertical slots 11 on the interior of the portion 5 of the valve casing at the top thereof. With this arrangement, the turning of head 18 will cause the disc 12 to move up and down in the portion 5 of the valve casing and without turning, provided the disc 15 is held in position by the cap 16 and the ears 13 engage slots 11, as will be described.

I provide an interior circular shoulder 21 just below the upper edge of the portion 5 of the valve casing. The distance of shoulder 21 below the upper edge of portion 5 is less than the thickness of disc 15, so that the latter may rest on the shoulder 21 as a support and always extend above portion 5. By this construction the cap 16 when screwed

on portion 5 may be turned down so as to lock the disc 15 and thus the stem 14 in position, which it does by pressing it against the shoulder 21. In this action of locking the disc 15 on the shoulder, the turning of the cap 16 will not turn the stem 14 because the threads of 14 are opposite to the threads of cap 16. The parts just described are shown all spread out in Fig. 2 and all assembled in Fig. 3.

In Fig. 3 I show the temperature controlled means for relieving the pressure at the inlet port independently of the operation of the valve closure 6. This means consists in a cartridge 24 which has the same general contour, shape, and construction as a revolver cartridge. The space that would ordinarily be used for the powder is left free and the fusible metal 27 at the end of the cartridge 24 corresponds with the bullet. The interior space of the cartridge has an opening 25 so that when the fusible metal 27 melts, the passage may be through the cartridge at the end and out through the side as indicated in Fig. 3.

In the interior tubular extension 4 of the valve casing, at the upper end of which the valve seat 8 is located, I provide a lateral opening 26 which has a valve seat adapted to receive the fusible metal 27 as its valve closure. The cartridge 24 has its head provided with a screw thread which engages the threads in an opening aligned with opening 26 and provided in the exterior walls of the valve casing 1. With this construction I can close the opening 26 by the cartridge 24 in a most effective manner by driving the cartridge with its soft nosed fusible metal nose against the valve seat of opening 26 by turning the cartridge home with a screw driver from the exterior of the valve casing. By reason of the fact that the valve closure for the opening 26 is of soft metal and can be turned down hard by a screw driver, the character of the valve seat does not need to be so carefully guarded because the soft metal will always find a seat by the manner in which it is forced into position. It is quite important in structures of this character to make sure that the by-pass valve is at all times tight except when the metal melts to open it. I believe I am the first to provide a temperature controlled by-pass valve by such simple and effective means as the cartridge construction which is illustrated.

In all temperature controlled valves in which the valve or by-pass is opened by means of the metal melting, it is a matter of considerable convenience to provide for renewing the fusible metal after it has once melted out in the structure. My construction as shown provides particularly convenient means for this purpose. As an additional matter of convenience, I provide a barrel holder 22 for a supply of cartridges.

This holder is of the same general construction as the cylinder of an old-fashioned revolver. It is held in position on the side of the valve casing 1 by means of a headed screw 23. In addition to the cartridge which is in position to close the by-pass, there are shown five other cartridges carried by the holder. The cylinder is cut away at one portion as indicated by the line 30 in Fig. 1, and the opening 31 in Fig. 3.

When it is desired to renew a cartridge, the old one with its nose melted out is unscrewed with the parts in the position shown in the drawings. The screw 23 is loosened and the cartridge holder turned around so that one of the new cartridges is aligned with the opening 26. Then the new cartridge can be turned into the opening through the valve casing 1 by a screw driver which turns the new cartridge in the threads of the holder, indicated at 33 in Fig. 3, until the threaded head of the cartridge leaves the thread 33, at which time the nose of the cartridge will be well on its way toward the opening 26, and then by merely pushing the screw driver and continuing to turn it after the threads of the cartridge reach the threads in the valve casing 1, the cartridge may be firmly driven to its functioning position.

The general operation of the pressure controlled relief means will now be described. With the parts shown most clearly in Fig. 2 all assembled as shown in Fig. 3, the safety valve is attached to the system or structure in which it is to be used so that the pressure to be relieved will have access through the inlet port 2. The cap 16 should be turned back so as to loosen its bearing on the disc 15. At this time any tension in the spring 10 will cause the disc 15 to rest against the horizontal portion of cap 16, but this will not prevent a screw driver turning of the head 18 and thus the stem 14.

With the pressure normal, the one setting the valve should relieve the spring 10 until the pressure causes the valve closure 6 to leak enough so as to permit a slight dripping through the outlet port 3. With the parts in this position, the stem 14 should be turned so as to lower the disc 12 and tension the spring 10 and close the valve casing 6 with a pressure determined by the desired factor of safety. Ordinarily a half or single turn of the stem 14 is sufficient, in a hot water heating system for example. As the stem 14 is turned, the disc 12 is lowered by a straight line movement without turning directly against spring 10, and thus the latter is tensioned without any twisting movement. This is important, because if the spring is tensioned by a twisting movement as well as by compression, the first operation of the valve will relieve the tension caused by twisting the spring and then the spring will not have its proper adjustment for its safety value,

which may cause the valve to leak when not desired for safety purposes. After the spring has been set as described by the straight down movement of the disc 12, the cap 16 is 5 turned down on its threads so as to bind the disc 15 and thus the stem 14 against turning.

With the cap 16 in its holding position, it is not possible to turn the stem 14 because the threads of the stem 14 are oppositely disposed 10 with respect to the threads of the cap 16, and they cannot turn together because there is a binding action due to the arrangement of the parts. In actual practice, the cap 16 can be turned down to its binding position by 15 hand.

The relation of the operating parts to the valve casing is such that no one of the parts protrudes from the valve casing. The latter surrounds and encloses all the vital parts of 20 the valve so that it is impossible to break off a part after the valve is in place. Furthermore, the parts are related to the valve casing so that the latter can be made of small size, 25 simple and attractive in appearance as compared with other specific types of safety valves.

To change the adjustment of the valve, some knowledge of the construction is required and this is an advantage because it prevents unauthorized or careless tampering with the 30 adjustment. The fact that the stem to adjust the spring is adequately protected by the cap and is locked in adjusted position by the cap is important. From an exterior view of 35 the valve the slotted head of the stem suggests a means to adjust the valve. But this means cannot be operated until the lock cap is turned back to relieve the disc on the adjusting stem cooperating with the cap for 40 locking purposes. This construction, therefore, discourages any offhand attempt to set the valve by unskilled persons and there is absolutely no means inviting children to 45 "monkey" with the valve as there is wherever a handle is presented in prior art purposes for adjusting purposes. I consider the exterior appearance of the valve and the effective means of locking the parts in adjusted position 50 important features of my improvements.

One of the real advantages in the temperature controlled relief means is due to the fact that the soft nose of the cartridge can be driven home to its position and in such movement will find or make its own seat for a 55 tight closure. So far as I know, I am the first to use the soft fusible metal for the double purpose of melting for opening the valve in an emergency and for forming the valve closure to insure a tight seat for the by-pass valve. That this whole arrangement can be 60 made with a cartridge inserted from outside the valve casing and without in any way disturbing the pressure operated safety valve parts, provides for real convenience and efficiency. The convenience of carrying extra

cartridges on the valve itself including the means for lining them up for insertion one by one, as needed, renders the safety valve as a whole more useful than it otherwise would be. If the valve blows off on account 70 of excess temperature, the means are ever present to reset the valve with a new fusible plug. Considering the fact that these valves are positioned with the plan of working only under intermittently unsafe and abnormal 75 conditions of the system, it is clear that only a few cartridges are needed to serve the valve for a very long time. In the ordinary use, the supply of cartridges will last as long as the valve because ordinarily the safety valve 80 remains in position for operation for years, without any large number of actual operations. Its principal function is to be always ready to operate.

I have now disclosed a safety valve having 85 improved features of construction.

What I claim is:

1. A safety valve comprising a valve casing provided with aligned openings and a drain opening, a valve seat between the latter and one of the former openings, a cap threaded on the casing to cover the other opening, a valve closure for said seat, a spring to adjust the pressure of the spring comprising 90 a stem, a disc threaded to the stem and having means cooperating with interior shoulders on the valve casing to prevent its turning, a second disc fast to the upper end of the stem and adapted to rest on a ledge of the 95 valve casing in position to be bound to the casing against turning by the said cap, all of said parts being located within the valve casing below said cap, said cap having an opening through which an operating head of 100 said stem is presented for turning to adjust said spring.

2. A safety valve comprising a valve casing provided with three openings, one for the inlet port having a valve seat, one for the 110 insertion of the valve parts, and one for a drain port; valve parts comprising a closure for said seat, a spring for the closure and means to adjust the spring pressure, a cap for the opening through which the valve 115 parts are inserted, said cap having a part to bear against the adjusting means to lock the latter in adjusted position.

3. A safety valve comprising a valve casing having a drain port, an inlet port, an 120 opening above the inlet port through which a valve closure, a spring therefor, and spring adjusting means may be inserted and aligned with the inlet port, a cap for said opening, cooperating means between the cap and 125 spring adjusting means to unlock and lock the latter in position by movement of the cap on the valve casing.

4. A safety valve comprising a valve casing having a drain port, an inlet port, an 130

opening above the inlet port through which a valve closure, a spring therefor, and spring adjusting means may be inserted and aligned with the inlet port, a cap for said opening, 5 cooperating means between the cap and spring adjusting means to unlock and lock the latter in position by movement of the cap on the valve casing, said cap having an opening through which the spring adjusting means 10 may be operated from outside the casing without removing the cap.

5. A safety valve comprising a valve casing having a drain port, an inlet port, an opening above the inlet port, a cap having 15 screw threaded connection with the casing for the latter opening, a pressure controlled valve closure for the inlet port, a spring bearing on the valve closure, spring adjusting means between the spring and cap and adapted to bear 20 against the cap and cooperating parts of the cap and adjusting means arranged to lock the latter in position when the cap is screwed down to holding position.

6. A safety valve comprising a valve casing having an enlarged central portion, a 25 lower portion for an inlet port having a tubular extension into the enlarged portion to provide a valve seat, an upper portion for an opening at the top and threaded to receive a 30 cap, an interior ledge slightly below the edge of said upper portion, interior diametrically opposite slots extending vertically and downwardly from said edge, a valve closure for said seat, a coiled spring mounted on the 35 valve closure, a disc having ears engaging said vertical slots and mounted on top of the

spring, a stem threaded through the center of said disc and provided with a fixed plate at the top to rest on said ledge and extend slightly above the edge of the upper portion, 40 means by which said plate may be turned, a cap threaded to the upper portion with opposite turns to the turns of the threads on said stem, said cap provided with an opening through which said means may be operated 45 and with a surface to bind said plate against turning when the cap is turned down tightly on the upper extension.

7. A safety valve comprising a valve casing, an adjustable pressure operable relief 50 valve closure in the casing, by-pass passage, means for pressure relief independently of the operation and adjustment of the pressure operable relief valve, said means comprising a valve seat for the by-pass passage, a cartridge with a threaded head piece and having a fusible metal nose adapted to make its closure on said valve seat tight, said valve casing having threads in its outer wall for receiving said head piece and to permit the 55 tightening of the by-pass closure by manipulation of the cartridge from without the casing.

8. The safety valve defined in claim 7 and including a cartridge carrier on the valve 60 casing adapted for movement to position a fresh cartridge into line with the by-pass valve seat for manipulation into operative position when the spent cartridge is removed.

In testimony whereof I have affixed my sig- 70 nature.

FREDERICK M. HOLMES.
